Primary Examiner — Patricia A Palasik(74) *Attorney, Agent, or Firm* — Studebaker & Brackett
PC(57) **CLAIM**

The ornamental design for a motion assistance apparatus, as shown and described.

DESCRIPTION

FIG. 1 is front perspective view of the front, right, and top sides of a motion assistance apparatus showing our new design;

FIG. 2 is a rear perspective view of the rear, left, and bottom sides thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of part 9 of FIG. 1; and,

FIG. 10 is an enlarged view of part 10 of FIG. 2.

The broken lines shown represent unclaimed subject matter of the motion assistance apparatus or environments and form no part of the claimed design.
